UNITED STATES PATENT OFFICE.

WALTER EGGINTON, OF CORNING, NEW YORK.

DESIGN FOR A GLASS VESSEL.

SPECIFICATION forming part of Design No. 36,233, dated February 24, 1903.

Application filed December 19, 1901. Serial No. 86,617. Term of patent 7 years.

To all whom it may concern:

Be it known that I, WALTER EGGINTON, a citizen of the United States, residing at Corning, in the county of Steuben and State of New York, have invented and produced a new, original, and ornamental Design for Glass Vessels, of which the following is a specification, reference being had to the accompanying drawings, forming a part thereof, 10 in which—

Figure 1 is a bottom plan view of the glass vessel having my design cut thereon. Fig. 2 is a transverse sectional view of the glass vessel having my design cut thereon.

15 The leading feature of my design consists in the central figure 1, the side lines of which at each alternate corner of the said figure are

extended and form the outline of the magnolia figure 2. At the other alternate corners of the figure 1 the said side lines of the ornamental figure cross each other and terminate against the side of the adjacent magnolia figure.

Having thus described my invention, the following is what I claim as new therein and 25 desire to secure by Design Letters Patent:

The ornamental design for a glass vessel substantially as herein shown and described.

In testimony whereof I hereunto affix my signature in the presence of two witnesses. 30

WALTER EGGINTON.

Witnesses:

THOMAS E. MORAN,
HARRY L. DOERSH.
